UNITED STATES PATENT OFFICE.

JAMES E. SINCLAIR, OF BALTIMORE COUNTY, MARYLAND.

VALVE.

SPECIFICATION forming part of Letters Patent No. 279,451, dated June 12, 1883.

Application filed January 29, 1883. (No model.)

To all whom it may concern.

Be it known that I, JAMES EDWARD SINCLAIR, of Baltimore county, State of Maryland, have invented a new and useful Improvement in Valves; and I do hereby declare that the following is a full, clear, and exact description of the same, reference being had to the accompanying drawings, forming part of this specification, in which—

10 Figure 1 is a central longitudinal section of the valve. Fig. 2 is an end view from the end C of Fig. 1. Fig. 3 is a transverse section through the line x x of Fig. 1, looking in the direction of the arrow. Fig. 4 is a longitudinal section of a hand-pump, showing my valve applied thereto.

15 My invention relates to an improved valve, designed mainly for pumping or hydraulic purposes, but applicable to all uses in which a 20 check-valve may be employed. It belongs to that class of valves in which an elastic or flexible tube is secured at one end to a circular shell or ring, while its other end is collapsed or flattened, which tube will allow fluids to pass 25 in one direction, but acts as a check for the reverse flow.

20 My invention consists in making said collapsible tube in two parts, one of which is fastened peripherally to one end of a shell, and 30 the other of which is fastened peripherally to the other end of the shell, while the two collapsible ends of said tube are fastened together, and one runs straight through the shell, while the other is folded upon itself.

35 It also consists in holding a collapsible tube both at its end and at its sides throughout its length to prevent it from doubling up, as will be hereinafter described.

40 In the drawings, A A' represent a metal shell, in which is arranged the flexible tubing, made of canvas, rubber, or any other material. One section of this tubing, B, is fastened peripherally to one end of the shell by a clamping-ring, C, screwed to the end of the shell, 45 and at this end is always distended or of circular form. This section of tubing runs straight through or nearly through the shell, and at its other end it is collapsed or drawn by an elastic edge to a straight diametrical line, forming a diametrical slit, as in Fig. 2. The other section of tubing, B', is secured peripherally to the other end of the shell by a clamping-ring,

55 C, screwed to the shell, and this section runs about half-way the length of the shell, and then, turning upon itself, has its free edge attached to the free or collapsed edges of the section B. This double construction of flexible tubing gives great strength to the valve, and when the water is checked it pockets in the folds of the section B' and compels the 60 section B to collapse at its end quickly. In a long collapsible tube of this character the collapse of the tube will frequently cause the tube to become doubled up and become disarranged and inoperative. To prevent this I make the 65 shell in two longitudinal divisions, A and A', with flanges a a', by which said divisions are bolted or screwed together. The flexible sections of tubing B and B' are also each made in 70 two longitudinal parts, and the edges of these longitudinal parts are caught between the flanges a a' of the two parts of the shell and there firmly clamped in place. This, it will be seen, holds the flexible tubing throughout its entire length in the shell upon each side 75 and effectually prevents any doubling up or any other objectionable action, and allows the valve to work perfectly and surely, with a normal opening and closing of its collapsible end.

80 In making use of this valve it may be connected with the lever of a hand-pump and reciprocated in a pump-barrel to raise or force water; or it may be embodied in a steam-pump; or it may be located in drains or sewers to act as a check-valve, and, besides these applications, is capable of very many other uses.

85 The valve has packing and rings at each end, which give steady and easy motion to the same, and the flexible tube opens to the full area and conforms to the shape of the inside of 90 pump, no matter whether round, square, or oval.

95 When the valve is used in connection with a hand-pump, as shown in Fig. 4, said valve is provided with studs p p on its opposite sides, near its middle and between the packing at the ends of the valve, and these studs play through slots in the side of the pump-cylinder, and constitute a point of attachment for the forked lever (not shown) which reciprocates it. To make an operative pump a stationary valve is arranged, as usual, in one end of the pump-cylinder, which may be the same construction as the movable valve, or any other

desired construction. The movable valve has also at each end a flexible and collapsible tubing, *t*, of canvas, which is connected to the ends of the cylinder, and forms a straight continuous passage for water, which prevents grit from getting into the wearing parts of the cylinder.

Having thus described my invention, what I claim as new is—

- 10 1. A valve composed of a shell or frame having within it a collapsible tube-section, *B*, running straight in the shell, and secured peripherally at one end, and a collapsible section, *B'*, secured peripherally at the other end, and re-
15 turned or folded upon itself, and having its free end connected to the free end of the other tube-section, substantially as described.

2. A valve consisting of a shell or frame made in two flanged longitudinal sections, combined with a collapsible tube secured peripherally to one end of the shell, and having its sides or edges clamped between the flanges of the shell, as shown and described.

20 3. The combination of the longitudinally divided and flanged shell *A A'*, the collapsible tube-sections *B B'*, secured peripherally at their outer ends, and having free collapsible edges at their other ends, and the clamping-rings *C C'*, substantially as shown and described.

JAMES EDWARD SINCLAIR.
